PARACHUTE

Samuel H. Knight, Lancaster, Pa.

Application September 19, 1930

Serial No. 482,971

6 Claims. (Cl. 244—21)

In the standard type of parachute, a plane passed vertically through the inflated sail and including its centre will cut it in a curve the central portion of which is approximately an arc of a circle of large radius, but the end portions will become rapidly more sharply curved toward the extremities of the curve formed by this intersection. The effort has been to extend the portion of the curve approaching a straight line to as great a part of the line described by the intersection of the sail by the vertical plane, and shorten the highly curved end portions of this line. Efforts have been made by departing widely from the accepted form of parachute, to produce such a preponderance of flattened area of the sail, but the well known general construction however has hitherto not been found to have been improved upon by these radical departures from it.

Another feature of the standard parachute that has been found objectionable is its tendency to oscillate, which is usually met by providing a vent at the central area of the sail. This diminished the slowing up of the descent. The standard parachute also has been difficult to pack so that it will open with rapidity and certainty. The removal from the pack and the opening out of the parachute of standard construction have presented difficulties. The parachute sail has usually been strung out vertically by a pilot parachute and other means have been adopted, with greater or less success to remove rapidly the parachute from the pack and to cause the prompt and rapid inflation of its sail.

My devices, while retaining the sail and the load ropes, allows the parachute to be placed more advantageously in a pack that did not depart from the standard form in a position and arrangement where the rapid and prompt opening of its sail was promoted, prevents oscillation to a large extent, presents a very large area of flatness of the sail and avoids the necessity of either a pilot parachute or a vent in the main parachute sail, though either of these instrumentalities may be used. No departure from the circular circumference of the sail is necessitated.

Figure 1 is a plan view of the upper face of the sail laid out flat the position of the upper portion of the load cords being indicated in dotted lines. Fig. 2 is a section on line 2—2 of Fig. 1.

The characteristic features of my device are the vertical fins the arrangement of the points of attachment of the additional load cords to

the sail, and the vertical air retaining fin or skirt around the periphery of the parachute. By the use of these devices, the total supporting surface of the sail will be made substantially flat, and the amount of fabric contained in the sail much diminished without diminishing the supporting area of the parachute. By reducing the fabric area of the sail the parachute may be stored in a much smaller container. The folding of the parachute is such that the peripheral edge is exposed immediately to the air, allowing the sail to inflate extremely rapidly.

The sail 1 of the parachute is fabricated in any suitable manner to form a flat disc. Load cords 2, are attached to this disc at its periphery. The additional load cords 3, 3, are attached to the inner portions of the parachute sail 1 and to the fins 5 and 6. The relative lengths of these cords 2 and 3 are regulated to make them function to flatten the sail.

The sail 1 has at the periphery the downwardly extending skirt 4, that extends preferably about the entire sail 1. This skirt may be made of a strip of textile material that is attached to the periphery of the sail. The load cords are attached to the skirt. It will readily be seen that there is a radially directed air pressure pressing outward the skirt 4 and tending to extend the sail laterally and to flatten it. This radial pressure will tend to push the skirt radially outward, and tend to keep it vertical when the parachute is in flight. I attach to the lower side of the sail a series of stabilizing fins, 5 and 6. These fins run circularly around the central point of the sail and are placed preferably at even distances apart. Baffles 7, 7 sometimes are placed radially to control any circular surge of the air around the spaces between them. The baffles are of textile material and preferably run radially. In most cases these baffles need not be used. In practice, I provide these fins with holes, d, d, to permit a portion of the air to pass them. The particular way the fins are attached to the sail is immaterial providing they are secured strongly to it. They may be made of textile fabric similar to the fin or skirt 4 and attached by sewing to the inside of the sail in their required positions. The additional load cords 3, 3, are attached to these fins. The particular construction above described lends itself to the strengthening of the sail at its portion where the greatest strain is imposed on it. The cords 3, 3, are carried over the central portion, between opposite sides of the fin. It will be folded by accordian pleating it in both directions.

105
110

The arrangements of the fins may be varied considerably from that shown and described above, and many changes made in the number and arrangement of the load cords and many other changes made without departing from my invention.

I claim

- 10 1. In a parachute the combination of a sail, and load supporting means, load cords extending from the load supporting means to the periphery of the sail and also to points thereon intermediate between its periphery and its centre, a skirt formed of textile material of substantially equal width throughout and of substantially equal circumference at its top and bottom and one or more circularly running fins extending downward from the lower part of said sail.
- 15 2. The device as defined in claim 1 in combination with baffles running radially and secured to the circularly running fins.
- 20 3. The device as defined in claim 1 wherein the load cords therein referred to are sewed to the skirt.

4. A parachute having a sail and load cords extending from points on the periphery of the sail to the load, and comprising a series of downwardly projecting fins sewed to the lower face of the sail, each fin being provided with seepage openings through it, and also comprising a series of additional load cords, extending from points on the sail between its periphery and its center, and secured to the fins.

5. The device as defined in claim 4 wherein the additional load cords are secured to the fins near the lower edges thereof.

6. In a parachute having a sail and load cords extending from the periphery of the sail to the load, the combination of a skirt formed of textile material of substantially equal length throughout and of substantially equal circumference at its top and bottom, one or more circularly running fins extending downward from the lower part of said sail, and baffles running radially and secured to the circularly running fins.

SAMUEL H. KNIGHT.
